(57) **CLAIM**

The ornamental design for a birdfeeder, as shown and described.

DESCRIPTION

FIG. 1 is an isometric view of a birdfeeder showing our new design.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a bottom perspective view thereof.

The broken lines in the Figures show portions of the birdfeeder that form no part of the claimed design.

The shade lines in the Figures show contour and not surface ornamentation or treatment.

1 Claim, 7 Drawing Sheets
